METHOD OF PRODUCING COLORED CONCRETE

Fred H. Amon, Weston, Mass., assignor, by mesne assignments, to Dewey and Almy Chemical Company, Cambridge, Mass., a corporation of Massachusetts

No Drawing. Original No. 1,910,419, dated May 23, 1933, Serial No. 520,717, March 6, 1931. Application for reissue April 22, 1938, Serial No. 203,713

5 Claims. (Cl. 106—24)

This invention relates to the art of producing colored concrete, and in the term concrete is included all compositions of cement and materials of mixed ingredients which have the property of 5 setting to produce a rigid structure.

My invention comprises an improved method of producing colored concrete, which is characterized by the use of powdered carbon black in the form of a liquid suspension. It includes also 10 within its scope the improved colored concrete herein described as produced by the method of my invention.

An important field of use of my invention is in the production of colored sections or stripes in 15 concrete road surfaces, imitation marble for interior finish, soda fountains, tiles, friezes, panels or the like. In the production of colored concrete, it has been the practice heretofore to employ carbon black in powdered or paste form. 20 However, in order to produce concrete having a color of satisfactory character and intensity, it has been necessary to include in its composition an amount of carbon black which has had a detrimental effect upon the strength of the resulting structure. For example, in order to produce a black concrete of acceptable color, it has been sometimes necessary to include as much as 25 10%, dry weight, of the carbon black, with a resulting reduction of compressive strength in 30 the set concrete to below 70% of that of uncolored concrete otherwise of the same composition. The present invention deals with this problem and its object is the production of colored concrete of high compressive strength, satisfactory 35 color and low pigment content.

For example, I have found it entirely practicable to produce with 3% content of dispersed carbon black a black concrete comparing favorably in color to that containing 10% carbon black 40 of commercial form, and in the structure so produced in accordance with my invention the reduction of strength resulting from the addition of the pigment does not exceed 3 or 4%.

For purposes of illustration, I will now describe 45 the practice of my improved method as applied to the production of a novel black or dark colored concrete, such as is suitable for road bed structure.

One satisfactory mixture for such uses includes 50 one part Portland cement, two parts sand and four parts gravel, all by dry and loose volumes. These ingredients, with the addition of the colloidally dispersed pigment about to be described, may be mixed and poured in accordance with the 55 usual commercial practice.

A liquid suspension of the carbon black may be prepared by stirring or beating the carbon black in water containing a suitable dispersing agent in approximately the proportions of one pound of carbon black to two pounds of water, thus producing a smooth paste. In this way a very definite and uniform separation or dispersion of the individual particles of carbon black is brought about and this is assisted by the addition of the colloidal dispersing agent. For such purpose may 10 be employed a soap solution, saponin, nigrosine, or any other material capable of acting as dispersing agent for the carbon black particles.

While it is practical under some conditions to employ carbon black of any commercial degree 15 of fineness, I prefer carbon black made by the channel or impingement process for in employing this pigment the desirable results above outlined are intensified, that is to say, a more intense color is secured in the product for a minimum 20 amount of pigment and the compressive strength of the resulting concrete is less reduced.

As an example of the result secured, it may be stated that a sample block of uncolored concrete of the composition above set forth possesses a 25 compressive strength of approximately 2275 pounds per square inch after setting for 7 days. When this same composition is colored by the addition of impalpable carbon black in colloidally dispersed form in an amount equal to 3% of the 30 cement employed, the compressive strength of the set concrete was reduced to 2245 pounds per square inch, which represents a reduction in strength of less than 2%. The color of the sample, however, in its intensity corresponds substantially to the color secured in the same mixture by the addition to the cement portion of 35 10% of commercial carbon black not colloidally dispersed and in a sample thus colored the compressive strength is reduced to 1500 pounds per 40 square inch, which represents a reduction in strength of about 34%.

Having thus described the improved method of my invention and its novel product, what I claim as new and desire to secure by Letters Patent of 45 the United States is:

1. The method of producing dark colored concrete without substantial loss of strength, which consists in forming a paste of a colloidal suspension of impalpable carbon black in water by the 50 addition of a colloidal dispersing agent, mixing said paste with the ingredients of the concrete, and subsequently pouring the concrete.

2. In a method of producing a dark colored concrete of relatively high compressive strength, 55

the step of adding to the concrete mixture carbon black in colloidal suspension in an amount approximating 3% of the cement content thereof.

3. In a method of producing an intense permanent black concrete of high compressive strength, the step of adding to the concrete mixture carbon black in an amount equal approximately to 3% of the cement content of the mixture, said carbon black being in colloidal suspension with nigrosine as a dispersing agent.
4. An improved dark colored concrete of relatively high compressive strength having distrib-

uted throughout its mass carbon black, the particles of which are dispersed in colloidal form in the concrete, as produced by the method of claim 1.

5. An improved dark colored concrete of relatively high compressive strength having distributed throughout its mass carbon black in colloidal form of an amount approximating 3% of the cement content of the concrete, as produced by the method of claim 2.

FRED H. AMON.
